UNITED STATES PATENT OFFICE.

WILLIAM T. JEFFERSON, OF PASADENA, CALIFORNIA.

PACKAGE.

Application filed November 8, 1922. Serial No. 599,626.

To all whom it may concern:

Be it known that I, WILLIAM T. JEFFERSON, a citizen of the United States, and a resident of Pasadena, in the county of Los Angeles and State of California, have invented certain new and useful Improvements in Packages, of which the following is a specification.

This invention relates to packages and particularly to a collapsible tube useful for dentifrice or toilet preparations. It is an object of the invention to provide a compound tube of the character described, adapted to hold two preparations; it is another object of the invention to provide a simple and efficient means whereby the tube may be suspended on a hook or nail in a sanitary manner.

In the drawings which represent an illustrative embodiment of the invention, Fig. 1 is an elevation of a tube constructed in accordance with my invention; Fig. 2 is a cross-sectional view thereof on the line 2—2 of Fig. 1.

25 I provide an elongated collapsible tube, upon which at the center is tightly clamped a flattened band 1 of suitable metal, which is additionally twisted as indicated at 2, to secure its grip upon the tube, and to provide the ring 3 by which the tube may be suspended.

The band 1 subdivides the elongated collapsible tube, into two collapsible tubes 4 and 5 which are joined together at their bases, and each of which is provided with a cover 6 and cap 7 in the ordinary way.

35 In the illustrated embodiment of the invention, the tube 4 contains dentifrice to be used in the morning, and for that reason is

covered with light enamel and marked with 40 the word "Morning". The tube 5 contains dentifrice to be used at night and for that reason is covered with a dark or black enamel and marked with the word "Night". Thus, in a simple, efficient, convenient package is provided a morning dentifrice and a 45 night dentifrice together with the means for clearly distinguishing the two and indicating which is to be used at each time.

The band 1 and ring 3, in addition to 50 forming an efficient means for subdividing the long tube into two tubes, provides a convenient and sanitary suspending means for the combined tubes.

I claim:

1. A container for dentifrice or the like comprising a length of collapsible tube having a flattened and closed median portion and capped at both its ends, whereby two connected tubes are provided. 55

2. A container for dentifrice and the like comprising a collapsible tube, a band clamped and flattened upon the tube intermediate its ends and dividing the same into two oppositely extending sections, closures 60 and caps at the outer ends of said tube. 65

3. A container for dentifrice and the like comprising a collapsible tube, a band clamped and flattened upon the tube intermediate its ends and dividing the same into 70 two oppositely extended sections, closures and caps at the outer ends of said tube, and a suspension ring formed in the band.

In witness whereof, I hereunto subscribe my name this 30th day of October, A. D., 1922.

WILLIAM T. JEFFERSON.
